United States Patent Office

Des. 178,588
Patented Aug. 21, 1956

178,588

DISH

Jack Woodson, Richmond, Va., assignor to Lurie Plastics,
Inc., Petersburg, Va., a corporation of Virginia

Application January 16, 1956, Serial No. 39,768

Term of patent 14 years

(Cl. D44—15)

FIG. 1.

FIG. 2.

I claim:

The ornamental design for a dish, substantially as shown.
